UNITED STATES PATENT OFFICE.

WILLIAM BOOTH, OF LEOMINSTER, MASSACHUSETTS.

HAND MIRROR AND BRUSH.

SPECIFICATION forming part of Letters Patent No. 351,958, dated November 2, 1886.

Application filed May 28, 1886. Serial No. 203,544. (No model.)

To all whom it may concern:

Be it known that I, WILLIAM BOOTH, of Leominster, in the county of Worcester and State of Massachusetts, have invented a new and useful Improvement in Hand Mirrors and Brushes, of which the following is a full, clear, and exact description.

Reference is to be had to the accompanying drawings, forming a part of this specification, in which similar letters of reference indicate corresponding parts in all the figures.

Figure 1 is front elevation of a hand mirror to which my improvement has been applied. Fig. 2 is a central longitudinal section of the same, taken through the line xx , Fig. 1. Fig. 3 is a plan view of the frame shown detached, part being broken away. Fig. 4 is a cross-section of a part of the same, taken through the line yy , Fig. 3. Fig. 5 is a plan view of the front plate of the handle.

The object of this invention is to provide hand mirrors and brushes formed of celluloid, or other suitable plastic material, in such a manner that they can be made at less expense and with greater facility than when made in the ordinary manner.

The invention consists in the construction and combination of the various parts of the hand mirrors and brushes, as will be herein-after fully described.

I will describe my improvement as applied to a hand-mirror, but do not limit myself to that use, as it can be applied with equal advantage to brushes.

A represents the back of the mirror, which is cut out of a thin plate formed between two rolls, and which can be ornamented to any desired extent by dies formed in the face of one of the rolls, the face of the other roll being

made plain to form a smooth surface to rest 40 against the glass of a mirror, or the stock of a brush. The front B of the handle is cut in the desired shape from a plate formed between two rolls.

C is the frame, which is formed by forcing 45 the plastic material through the ordinary stuffer, producing a long straight strip with a groove, D, in one side, and which is then cut into pieces of such a length as will form frames of the desired size. These pieces are then 50 bent into the required shape upon formers.

The groove D is made of such a width as will receive the edges of the back A, the glass E, or the brush-stock, and the front plate, B, of the handle. The ends of the frame C are 55 then fitted to each other and are cemented together.

Having thus fully described my invention, I claim as new and desire to secure by Letters Patent—

1. An improved frame for hand mirrors or brushes, consisting of a back plate, a handle front plate on the handle-extension of the back plate, and a grooved band-frame surrounding the whole, substantially as herein 65 shown and described.

2. In hand mirrors and brushes, the combination, with the plate E, of the back plate, A, the handle front plate, B, on the handle-extension of the back plate, and the band-frame C, 70 grooved in its inner side to receive the edges of the plate or block, the back plate, and the handle front, and surrounding the whole, substantially as herein shown and described.

WILLIAM BOOTH.
